CLAIM

The ornamental design for a combination electric toothbrush and holder, as shown and described.

DESCRIPTION

FIG. 1 is a front, top and right side perspective view of combination electric toothbrush and holder, showing my new design;

FIG. 2 is an exploded view of the components as shown in FIG. 1;

FIG. 3 is a rear, bottom and left side perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines shown in the drawings illustrate features of the article of manufacture that form no part of the claimed design.
